UNITED STATES PATENT OFFICE

105,253

DESIGN FOR TUCKED TEXTILE FABRIC

John P. Young, Chicago, Ill., assigner to Advance
Button and Pleating Co., Chicago, Ill., a cor-
poration of Illinois

Application May 6, 1937, Serial No. 69,207

Term of patent 3½ years

To all whom it may concern:

Be it known that I, John P. Young, a citizen
of the United States, residing at Chicago, Cook
County, and State of Illinois, have invented a new,
original, and ornamental Design for Tucked Tex-
tile Fabric, of which the following is a specifica-
tion, reference being had to the accompanying
drawing, forming part thereof.

Fig. 1 is a front elevation of a fragment of a
piece of tucked textile fabric showing my new
design.

Fig. 2 is an edged view thereof looking in the
direction of the arrow 2 in Fig. 1.

In the drawing the surface ornamentation, seen
along the tucks, represents braid or similar mate-
rial sewed into the tucks and said surface orna-
mentation is repeated throughout the design.

I claim:

The ornamental design for tucked textile fabric
as shown and described.

JOHN P. YOUNG.
